RACE TRACK

Anthony W. Molinare, Oak Park, Ill.

Application March 13, 1939, Serial No. 261,517

2 Claims. (Cl. 272—4)

The present invention relates to race tracks, and more particularly to tracks of the type used for animal or vehicle racing.

Race tracks heretofore employed for animal racing, such as for horse or dog races, have usually been constructed in the form of an oval including straight parallel sides or runways connected at their corresponding ends by curved runway portions, providing a continuous course of predetermined length. It has been found highly desirable to present for the interest, thrill, and amusement of spectators at such races, a racing program which includes a multiplicity of races, several of which are of different lengths. It has also been the practice to locate the finish line in front of or in close proximity to the spectators' and judges' stands. In order to provide for termination of all races at a finish line in the locale of the spectators, it has been necessary to start certain races (the length of which is less than or in excess of the length of the complete oval course) at points remote from and generally out of normal range of vision of the spectators, which greatly detracts from the interest and entertainment of the spectators. It is well known that many spectators become greatly thrilled and amused in observing the commencement of a horse race, and due to present types of race track constructions, such joys and entertainment must necessarily be restricted to only those races that start in front of the spectators.

The primary object of the present invention is to provide a simple and novel race track construction including a plurality of oval race courses of different predetermined lengths, each of said courses having portions coincident with portions of one or more of the other oval courses.

Another object of my invention is to provide an improved race track of the character indicated including a plurality of oval race courses of different predetermined lengths, each of said courses having straight portions coincident with straight portions of one or more of the other oval courses, together with a gate, adjacent the juncture of the end of one of the coincident straight portions of the course with a curved portion, for selectively rendering available a race course of desired length.

A further object is to provide an improved race track of the character indicated, which is formed to permit starting and finishing of races, on each of said plurality of different length courses, substantially in front of the mass of spectators, to enhance the interest, thrills, and entertainment of said spectators.

Other objects and advantages of the present invention will be apparent from the following description taken in connection with the accompanying drawing, in which:

Fig. 1 is a diagrammatic illustration of a race track constructed in accordance with the present invention.

Fig. 2 is an enlarged, fragmentary, diagrammatic illustration of the juncture of two oval courses of different lengths, showing a gate movable to either of two positions for selectively rendering operative one of said courses.

Fig. 3 is a front elevation of the gate, taken as indicated at line 3—3 on Fig. 2.

Fig. 4 is a fragmentary end view of the gate, taken as indicated at line 4—4 on Fig. 3.

In the illustrated embodiment of my invention, the race track is shown as comprising four oval courses of unequal length, each having portions superimposed upon and coinciding with similar portions of one or more of the other courses. Said track includes two parallel, spaced-apart, straight side portions of equal length, indicated at 10 and 10^a, which are connected at corresponding ends by curved portions 11 and 11^a. The straight side portions are also connected, intermediate their length, by curved portions 12 and 12^a, which are similar to and spaced inwardly from the respective curved end portions 11 and 11^a unequal distances. By virtue of this arrangement, it is possible to obtain, within the area of a conventional oval race track, four oval race courses of different lengths, as will be presently described.

For convenience, the starting line and finishing line are indicated at the same place, and designated by reference numeral 15. Desirably, although not essentially so, said line 15 is located centrally of the length of the smallest oval course defined by curved portions 12 and 12^a, and it is to be understood that said starting and finishing line is located in front of the stands of the spectators and judges.

The largest of the four oval race courses includes the straight side portions 10 and 10^a and the curved end portions 11 and 11^a, and the path of travel around the course is indicated by a semi-head type arrow designated as 16. The next largest oval race course includes the major part of the straight side portions 10 and 10^a, curved end portion 11, and the inner curved portion 12^a, and the path of travel around said course is indicated by a full head type arrow designated as 17. The third largest oval course includes parts of the straight side portions 10 and

10^a, curved end portion 11^a, and the inner curved portion 12, and the path of travel around said course is indicated by the semi-tail type arrow designated as 18. The smallest oval course includes intermediate parts of the straight side portions 10 and 10^a and the inner curved portions 12 and 12^a, and the path of travel around the course is indicated by a full tail type arrow designated at 19. It will now be apparent that the last three courses described have portions thereof superimposed upon and coincident with portions of the largest oval race course, thus producing a compact association of four different length race courses lying within the area or confines of one single or major race course.

15 By virtue of the construction described, the interest, thrills, and amusement of the spectators will be greatly enhanced because, irrespective of the size oval course selected for the race, provided the length of said race corresponds to the size oval course selected, it is possible to observe both the starting and finish of every race run on the different size oval courses.

20 To assist in defining the race course to be used, I provide two similar movable gates, designated at A and B, located respectively at the junctures of straight portion 10^a with the inner curved portion 12, and straight portion 10 with the inner curved portion 12^a. These gates may be of any suitable or desired form and as shown, each is composed of a gate member 21, hingedly supported at 22, at one end on an upright standard 23 located at one side of the main straight portions 10 and 10^a, respectively. At tie rod 24, with an interposed turnbuckle 25 connects the free end of the gate to the upper end of the standard 23, and assists in properly supporting the load of the gate. Because these gates are of substantial length, and to facilitate movement of the gate member, I employ one or more journaled wheels 27, mounted in brackets 28, on the lower edge of the gate member 21 in engagement with the ground. These gates are adapted to be moved to either of two positions of adjustment, as seen in full and dotted lines in Figs. 1 and 2, depending upon the size oval course to be employed.

25 In order to facilitate a more clear and full understanding of the invention, let it be assumed that the length of the main or largest oval course, defined by straight portions 10 and 10^a and curved end portions 11 and 11^a, is one mile. Then by proper relationship of curved inner portions 12 and 12^a to each other and to the respective curved end portions 11 and 11^a, the next largest oval course may be seven-eighths of a mile in length; the third largest oval course, three-quarters of a mile in length; and the smallest oval course, five-eighths of a mile in length. By variation in location of the curved inner portions 12 and 12^a relatively to each other

and to the respective curved end portions 11 and 11^a, it is possible to obtain a relatively great number or sizes of the last three oval courses mentioned.

30 When it is desired to utilize the largest oval course, the gates A and B are in closed position, as seen in Fig. 1 of the drawing. If the next largest size oval course is to be employed, gate B is swung to the dotted position across the straight portion 10, while gate A remains in position as seen in full lines in Fig. 1. To obtain use of the third largest size oval course, gate A is moved to the dotted line position, across straight portion 10^a, while gate B is in closed position, as seen in full lines. In order to utilize the smallest oval course, the gates A and B are moved to the dotted line positions indicated, across the straight portions 10 and 10^a as seen in Fig. 1.

35 It will be apparent that the race track embodying the present invention may also be advantageously employed in connection with various types of races, such as "midget" automobile races, dog races, etc.

40 While I have illustrated and described a preferred embodiment of my invention, manifestly it is capable of modification and rearrangement without departing from the spirit and scope thereof. I do not, therefore, wish to be understood as limiting this invention to the precise form herein illustrated and described, except as I may be so limited by the appended claims.

I claim:

45 1. A race track comprising two oval courses each having straight long side portions and short curved end portions, said ovals having minor axes 35 of the same dimension and major axes of different dimensions and superposed with the straight side portions of each coincident throughout their common extent, the oval with the shorter major axis being non-symmetrically placed within the 40 larger oval whereby the corresponding curved end portions of the two ovals are spaced different distances apart, thereby to provide four oval race courses of different lengths.

50 2. In a race track of the character set forth in claim 1, a gate movably mounted at the intersection of a curved end portion of the smaller oval with the straight side portion of the larger oval, said gate being movable to an inclined position across the straight portion of the large oval and substantially in line with the outer periphery of said curved end portion of the smaller oval, or to a position across said curved end portion of the small oval and substantially in line with the inner edge of the straight side portion of the long oval whereby to selectively direct racers about either the curved end portion of the short oval course or about the curved end portion of the long oval course, respectively.
